UNITED STATES PATENT OFFICE.

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR SHAPING UPPERS OVER LASTS.

Application filed June 13, 1919, Serial No. 303,819. Renewed November 23, 1923.

To all whom it may concern:

Be it known that I, BERNHARDT JORGENSEN, a subject of the King of Denmark, residing at Beverly, in the county of Essex and State of Massachusetts, have invented certain Improvements in Machines for Shaping Uppers Over Lasts, of which the following description, in connection with the accompanying drawings, is a specification, like reference characters on the drawings indicating like parts in the several figures.

This invention relates to machines for use in the manufacture of boots and shoes for shaping uppers over lasts, and in many of its aspects has reference more particularly to pulling-over machines.

One important object of the invention is to provide a pulling-over machine adapted for use in the manufacture of a type of shoe commonly known as an "arctic" shoe or an overshoe. The characteristic shoe of this type has a cloth upper faced round its lower margin with a band of rubber, and a rubber sole which is united by vulcanization to the rubber portion of the upper materials. In the process of manufacture the upper is lasted over an insole of unvulcanized compound, which may be channeled round its edge to receive the overlaid margin of the upper, and after the lasting the outsole is laid and the shoe is vulcanized. The upper materials, as assembled on the last prior to lasting, present an unusual lack of conformity to the contour of the last, this condition being due in large measure to the practice of cutting the entire forepart of the fabric upper in a single piece. Such an upper, when assembled on the last, tends to "bridge" in a marked degree from the toe end to the cone of the last with a consequent displacement from the edge of the last bottom of the margin of the upper along the sides of the ball and in the shank. The difficulties in presenting such a shoe in position to be engaged properly by the grippers of pulling-over machines as heretofore constructed, and the failure of such machines to pull and secure the upper satisfactorily in conformity to the contour of the forepart of the last, particularly over the instep, have necessitated heretofore that the upper pulling and fastening operations on

this particular type of shoe be performed by hand.

The present invention provides a machine particularly adapted for pulling over shoes which present conditions such as those above described. Important features of the invention are to be recognized in a novel construction and arrangement of upper pulling and fastening means for operating upon an upper along the side of the last to pull it transversely over the last and secure it in its pulled condition. In the machine herein shown the upper pulling means at each side of the last comprises two pairs of gripper jaws with the rear pair constructed and arranged to engage portions of the margin of the upper at the ball of the last and along the inwardly receding curve of the edge of the last bottom at the rear end of the ball, this pair of gripper jaws being curved inward laterally of the shoe along said inwardly curved edge and also having their outer or lower edges inclined in substantial conformity to the slope of the bottom surface of the last from the ball line rearwardly. The grippers, moreover, are so positioned that the rear pair of jaws project initially farther downward than the front pair. As thus constructed and arranged, the grippers are positioned conveniently for the reception of the marginal edge of the upper materials when the work is presented to the machine, notwithstanding abnormal downward displacement of the margin of the upper along the sides of the last relatively to the plane of the shoe bottom, and by reason of the construction and arrangement of the rear gripper jaws the upper is pulled comparatively close to the lateral surface of the last at the rear end of the ball as well as farther forward and in the overdrawing operation of the grippers is pulled tightly inward over the receding curves of the last at the rear of the ball. Still further to insure that the machine shall operate to pull and conform satisfactorily to the contour of the last the comparatively wide section of upper material extending over the instep, the gripper operating means herein shown is so constructed that the rear pair of gripper jaws at each side receive a longer upper pulling movement than the front pair. In order

to retain the advantage secured by pulling the upper as above described, the upper fastening mechanism of the machine is constructed and arranged to drive a tack at each side of the shoe substantially at the rear end of the ball of the last in addition to tacks driven farther forwardly. To insure that the rear fastenings shall be properly located to hold the upper where the edge of the shoe bottom curves inwardly toward the shank, the rear tackers are arranged to be positioned by engagement with that part of the shoe where said edge curves inwardly, and a further feature of the invention is to be recognized in the construction and arrangement thus provided.

It is contemplated that an organization embodying some or all of the features above set forth will have important advantages in the manufacture of other types of shoes as well as of the type described. In the manufacture of various kinds of shoes, including welt shoes, it has been found practically necessary heretofore, in order that the upper may be properly stretched and conformed to the last over the instep and so positioned in the shank as to permit the side lasting machine to operate upon it with the best results, to supplement the pulling-over operation as performed by the pulling-over machine by mounting the shoe on a spindle and pulling the upper at or near the rear end of the ball on each side of the shoe with hand pincers before the shoe is presented to the side lasting machine. The present invention, by its provision in a pulling-over machine of means for pulling and for fastening the upper in the manner above described, eliminates the need for this supplemental manual pull and permits the shoe to be presented directly to a machine for lasting the shoe along the sides.

Associated with the upper pulling and fastening means in the machine shown is an improved construction and arrangement of overlaying means whereby the margin of the upper is pressed inwardly over the insole and properly positioned and held for the reception of the upper fastening tacks, and further important features of the invention are to be recognized in the combination thus provided and in details of the overlaying mechanism. An advantageous novel characteristic of the construction illustrated consists in provision for relative yield of overlaying members which are arranged to operate in different locations along the edge of the shoe bottom, for example at opposite sides of a fastening point, to insure effectiveness of the different members notwithstanding variations in contour of the bottom of the last. Such a construction is of particular utility where the different members are arranged as shown to operate, one at the ball of the last, and the other over

the receding curve of the portion of the shoe bottom at the rear of the ball, the provision for relative yield permitting these members to operate with equally effective results to hold the different portions of the upper prior to the tacking. A further advantageous characteristic consists in provision for relative adjustment of the overlaying members, permitting the rearmost member, for example, to be positioned initially lower than the member which operates farther forwardly to insure its effectiveness over a relatively lower portion of the bottom surface of the inverted shoe at the rear of the ball line. The provision for relative adjustment of the different members also involves advantages in adapting the machine for operation upon shoes of different sizes and of different materials.

The above and other features of the invention, including also a novel construction and arrangement of fastening mechanism, and certain details of construction and combinations of parts will now be described with reference to the accompanying drawings and pointed out in the claims.

In the drawings,—

Figure 1 is a view in side elevation of the head portion of a pulling-over machine in which the invention is embodied, illustrating the initial position of the work;

Fig. 2 shows on a larger scale a last and an upper with the side grippers positioned as they appear in relation to the work at the time when the work is initially presented;

Fig. 3 is a perspective view illustrating the relation of the upper pulling means and of the overlaying and fastening means to the shoe and showing the parts as they appear at the end of the upper pulling operation.

Fig. 4 is a perspective view showing the overlaying and tacking means at one side of the shoe in the position which it assumes at the end of its inward movement over the shoe;

Fig. 5 is a perspective view of one of the rearmost side tackers and its associated overlaying mechanism; and

Fig. 6 is a plan view showing one side portion of the shoe as it appears after the upper has been pulled over and fastened, and illustrating further the relation between the shoe and the different operating instrumentalities.

The invention is herein illustrated as incorporated in a well-known type of pulling-over machine, characteristic features of which are shown and described in detail in various prior United States Letters Patent including particularly Patent No. 1,029,387, granted on June 11, 1912 upon an application of R. F. McFeely, and in view of such prior disclosure the present description will

be limited to such details of the general organization of the machine as it is necessary to refer to for an understanding of the invention.

For pulling the upper at the toe end of the last the machine has a toe gripper comprising jaws 2 curved and extended for engagement with a considerable portion of the margin of the upper round the toe end of the last, these jaws being mounted on a gripper casing 4 and operated by a gripper bar 6 which is connected to an updraw lever 8. Operative movement is imparted to the lever 8 by means of a cam 10 on a cam shaft 12 through a cam slide 14 and a spring 16 which forms a yielding connection between the cam slide and the rear end of the lever. For pulling the upper at the sides of the last the machine has side grippers the construction of which will be hereinafter more particularly described, these grippers being mounted on gripper bars 18 connected to side updraw levers 20. The levers 20 are operated similarly to the toe gripper lever 8 by means of a cam 22 on the cam shaft 12 through a cam slide 24 and springs 26. To support the last against the pull of the grippers in the upper pulling operation the machine has a sole rest 28 which is pivotally mounted and is rocked downward slightly by means of a cam 30 during the pulling movement of the grippers to press the last into the upper. A heel rest 32 also is moved at the time of the upper pulling operation into positioning and supporting engagement with the heel end of the shoe.

In the operation of machines of this type the pulling of the upper by the several grippers is effected in the first stage of the cycle of operations, after which the machine comes to rest to permit inspection of the work and any adjustment which the operator observes to be necessary. When the machine is again started, shoe holding and supporting devices which are mounted on side clamp arms 34 are swung inward into operative relation to the shoe, and either immediately thereafter, or following a second pause in the cycle of operations, the toe and side grippers are rendered effective to draw the margin of the upper inwardly over the last bottom and the several overlaying and tacking devices are operated to press different portions of the margin of the upper into proper relation to the insole and to fasten them in place. The overdraw movement of the toe gripper is effected by overdraw springs 36 and the accompanying overdraw movement of the side grippers by springs 38 (Fig. 3), the inward movement of these several grippers being controlled by the well-known mechanism provided in machines of the illustrative type as shown and described in detail in said prior patent. The overlaying and tacking mechanism for the

toe end of the shoe is mounted upon a front arm 40 and comprises a wiper plate 42 and a tack driver 44, the arm 40 receiving its rearward operative movement from a slide 46 to which the arm is connected. The side 70 overlaying and tacking mechanisms, the construction of which will be more fully described hereinafter, are carried by side arms 48 which are swung inward laterally of the shoe in unison with the rearward swinging 75 movement of the arm 40. The details of the mechanism for imparting operative movement to the arms 40 and 48 and for operating the several tack drivers are not herein particularly illustrated in view of the prior 80 disclosure of said McFeely patent which may be referred to for a more complete understanding of this and other features of the general organization of the machine.

The side grippers on each side comprise a 85 front pair of gripper jaws 50 which are arranged to engage the margin of the upper along the side of the last near the toe end, and a rear pair of gripper jaws 52 arranged to engage a portion of the upper along the 90 ball of the last, these grippers extending rearwardly a sufficient distance to engage also a portion of the upper at the beginning of the shank. The gripper jaws 52 are curved laterally of the shoe in substantial 95 conformity to the inwardly receding curve of the edge of the last bottom at the rear end of the ball of the last, and as shown in Fig. 2 the outer or lower edges of these jaws are inclined downward similarly to the 100 lengthwise slope of the last bottom rearwardly from the ball line. The jaws 50 and 52 are mounted respectively on separate gripper casings 54 and 56 to permit relative pulling movements between the front and rear pairs of jaws. It will be understood 105 that the closing of the jaws is effected by relative movement between the gripper casings and the bar 18 assisted by the usual closing springs as the bar is moved upwardly 110 and that in its continued movement the bar operates the gripper casings to cause the grippers to pull the upper through connections including an equalizing lever 58 which permits relative movement between the two 115 casings in response to differences in resistance of the different portions of the upper, this duplex construction and arrangement of gripper operating means being similar to prior constructions as shown and described 120 more in detail in United States Letters Patent No. 1,030,522, granted on June 25, 1912 upon an application of R. F. McFeely. It will be understood that initially the grippers are held with the gripper jaws in open 125 condition in consequence of engagement of ears on the gripper casings 54 and 56 with stop shoulders 60 and 62 on a portion of the frame of the machine. In the present construction the shoulder 62 is lower than the shoulder 60, resulting in a depression of 130

the gripper jaws 52 relatively to the jaws 50, as shown in Fig. 2, to facilitate engagement of the jaws initially with the margin of the upper. In consequence of this arrangement and by reason of the relatively greater yield laterally of the shoe of the portion of the material extending between the opposite pairs of rear jaws 52, due to its greater width and its loose condition on the last, the latter jaws are moved farther than the jaws 50 in the upper pulling operation, the strains being substantially equalized and the grippers coming to rest with the different portions of the upper stretched and conformed with equal effectiveness to the contour of the last.

Portions of the side overlaying and tacking mechanisms carried by the arms 48, comprising overlaying wipers 64 and 66, tack holders 68 and 70, and tack drivers 72 operated by a driver bar 74, are similar to the overlaying and tacking mechanism carried by the front arm 40, mechanism of this general type being described more in detail in prior Patent No. 1,029,387 and in Patent No. 1,135,954 granted on April 13, 1915 upon an application of R. F. McFeely. It will be understood that the wiper plates 64 and 66, similarly to the wiper 42 on the front tacker arm, are yieldingly positioned by springs 76 (Fig. 1) in such manner as to engage the margin of the upper substantially opposite to the edge of the insole as they move inwardly and then to yield upwardly in their continued inward movement in response to resistance of the shoe materials, the springs rendering the wipers effective to press the margin of the upper down upon the insole and to hold it in position for tacking. As illustrated, the tack holder 68 is arranged to hold two tacks in position to be driven at or near the usual tip line location on such shoes as are provided with tips, and the tack holder 72 is arranged to hold a single tack in position to be driven a short distance in the rear of the tip line location. It will be understood that these tack holders and the corresponding drivers are swiveled on their supporting arms for self-adjustment together in the manner explained in the earlier patents in accordance with the lengthwise contour of the lateral periphery of the shoe, the extent of inward movement of the tacker arms and the consequent distance of the tacks from the edge of the shoe bottom being determined by engagement with stops carried by the underlying side clamp arms 34.

It will be seen by referring particularly to Fig. 4 that the present machine is provided with means for overlaying and fastening a portion of the margin of the upper at each side of the shoe in the rear of the wiper 66, including means for driving a tack substantially at the rear end of the ball of

the last. For this purpose each arm 48 carries on its rear side a tacker plate 80 mounted on a pivot 78 for swinging movement transversely of the edge of the shoe bottom. The tacker plate 80 carries a tack holder 82 herein shown as constructed substantially as illustrated and described in United States Letters Patent No. 1,279,491, granted on September 24, 1918 upon an application of Orrell Ashton. Associated with this tack holder is a driver rod 84 arranged to be operated by a swinging arm 86 which is pivoted on the plate 80 and slotted to receive a pin 88 projecting from the driver bar 74. A spring 90 connected at one end to a pin 92 on the plate 80 and at its other end to a pin 94 which projects from the bar 48 through a slot 96 in the plate 80 tends to swing the latter plate and its supported tacking mechanism toward the shoe as far as permitted by the pin 94. The tacker plate 80 and the mechanism carried thereby thus occupy initially an abnormally advanced position relatively to the other portions of the side tacking mechanism. As the arm 48 is swung inwardly toward the shoe a stop member 98 on the lower end of the plate 80 is carried into engagement with that portion of the side of the shoe where the edge of the shoe bottom begins to curve inwardly and limits the inward movement of the rearmost tacker, the spring 90 then yielding to permit continued movement of the arm 48 to its limit determined by engagement with the stop on the side clamp arm. The member 98 thus determines the distance between the rearmost tack and the edge of the shoe bottom independently of the other tacking devices, insuring that this tack shall be driven in the proper location notwithstanding pronounced variations in the curvature of the lateral periphery of the shoe. In order to guard against injury to the surface of the upper in the rocking movement of the tacker plate 80 after the member 98 has engaged the shoe, this member in the construction shown comprises a roll for engagement with the shoe materials, the roll being mounted upon a holder 100 secured adjustably by means of screws 102 to the tacker plate 80. By adjustment of the holder 100 the member 98 may be positioned to cause the tack to be driven at different distances from the edge of the shoe bottom.

Pivoted on the lower end of the tacker plate 80 below the tack holder 82 are a pair of overlaying members 104 which, in view of their characteristic function, may be conveniently termed "wipers," these members in the construction shown having at their front ends rolls 106 to assist in eliminating undesirable friction against the upper at the edge of the shoe bottom. Springs 108 connected to the members 104 and to the pins 92 tend to swing these mem-

bers about their pivots in a direction for applying holding pressure to the margin of the upper on the shoe bottom while permitting them to yield each independently of the other in response to resistance of the shoe materials and in conformity to variations in the contour of the bottom face of the shoe. The normal position of one of the pair of members 104 is determined by an adjustable eccentric stop 110 against which the member is held by its spring 108, this stop being integrally formed on a stud 112 which projects through the plate 80 and upon which is mounted an eccentric collar 113 (Fig. 4) for positioning engagement with the other member 104. A nut 114 on the end of this stud may be tightened to secure the different eccentric members in adjusted position. The provision of these independently adjustable members permits the different overlaying members 104 to be definitely adjusted as desired relatively to the plane of the shoe bottom in order to render them equally effective, for example, upon the different portions of the margin of the upper at opposite sides of the rearmost tacking point, including a portion overlying the rearwardly sloping contour of the shoe bottom at the rear of the ball. It will be noted by reference to Fig. 5 that the rearmost member 104 is positioned lower than the other member with particular view to effectiveness in operating upon such portions of the shoe and by reference to Fig. 6 it will be seen that this member also projects a little ahead of the other member in view of the inward lateral curve of the edge of the shoe bottom at the rear of the tacking point. The provision for adjustments of these different members is also of advantage in adapting the mechanism to different shapes of shoes as well as for varying, if desired, the overlaying pressures in accordance with differences in the condition of different shoe materials. The rearmost tackers and their associated overlaying devices are arranged to operate substantially upon the portions of the upper which are pulled by the rear gripper jaws 52 and to drive their tacks in locations lengthwise of the shoe near the rear ends of said jaws.

In the operation of the machine, briefly summarized, the operator presents a shoe with its insole against the sole rest 28 and in the correct lengthwise position determined by the jaws 2 of the toe gripper, and after arranging the margin of the upper properly within the open jaws of the several grippers depresses the starting treadle. Immediately following the starting of the machine the several gripper levers are upraised, causing the gripper jaws to close upon the upper and then to pull it over the last, the pulling operation of the grippers being accompanied by a slight downward rocking movement of the sole rest effected by the cam 30. In this

operation the rear gripper jaws 52 are moved upward farther than the front jaws 50 on each side to cause the upper to be properly pulled and conformed to the contour of the last over the instep as well as farther forwardly, as hereinbefore explained. At the end of the upper pulling operation the machine comes automatically to a stop with the upper held under tension to permit inspection and any necessary adjustment. Following a subsequent starting of the machine the side clamping and supporting devices 34 are swung into operative position, and the toe and side grippers are then released to the action of their overdraw springs to cause them to pull the margin of the upper inwardly over the edge of the shoe bottom, the inward movement of the grippers being accompanied by a similar movement of the toe and side tacker arms which force the several overlaying members or wipers into engagement with the tensioned upper and finally trip the grippers to cause them to release their hold upon the stock in the manner characteristic of machines of this general type. It will be understood that in this inward movement of the tacker arms the overlaying members are permitted to yield backwardly in response to resistance of the upper held by the grippers, as well as upwardly, provision for such backward yield of the members 104 being afforded by the springs 90 which control the supporting plates 80, and that when the grippers are tripped the several overlaying members are instantly forced farther inwardly as well as downwardly to prevent the upper from relaxing before the tacks are driven. The tacker arms having completed their inward movement, and the rearmost tackers on the plates 80 having adjusted themselves relatively to the edge of the shoe bottom, the several tacks are driven in the manner characteristic of machines of this general type, after which the parts return to their starting position and the shoe is released.

It will be evident that the side grippers constructed and arranged as hereinbefore described are not only positioned initially for convenient engagement with the margin of the upper, notwithstanding its abnormal relation to the plane of the shoe bottom in a shoe of the type illustrated, but also serve in the upper pulling and over-drawing operations to pull the upper closely over the entire forepart of the last including the instep and to stretch and conform the upper to the contour of the last at the rear end of the ball as well as farther forwardly. In securing this result the shape of the rear gripper jaws is important, since by substantial conformity to the lateral curve the edge of the shoe bottom as well as to the rearward sloping contour of the bottom surface of the last at the rear

70

120

125

130

of the ball these grippers are rendered effective to pull the different portions of the margin inwardly substantially equal distances from the edge of the insole and in 5 equally close relation to the plane of the insole, thus insuring uniformity in the tightening of the upper and permitting the overlaying members 104 to follow the overdrawn margin closely and to clamp and hold it effectually at opposite sides of the tacking point until the tack is driven. The location of the rearmost tack at or near the rear end of the ball insures that the upper shall be held closely conformed to the inwardly receding curve of the last at the beginning of 10 the shank and shall lie substantially close to the edge of the insole along the shank in preparation for subsequent operations.

It will be understood that the invention 20 is by no means limited in utility to the manufacture of shoes of the particular kind herein illustrated, but is applicable to the manufacture of various types of shoes including welt and turn shoes as well as 25 shoes of the McKay type, and to shoes made of various materials. Following the operation of this machine the shoe herein shown may be presented to a side lasting machine for overdrawing and fastening the upper 30 along the shank, as well as to complete the overlaying operation round the toe, or these portions of the margin may be drawn over the edge of the insole and fastened in any other suitable way, the shoe in any 35 case being in such condition following the operation of the present machine as to obviate any necessity for pulling the upper to any substantial extent either in the shank or in any other part in order to conform 40 it in the desired manner to the contour of the last. It is contemplated that in the case of welt or turn shoes on some kinds of work the shoe as it leaves this machine will be in such condition in the shank portion 45 as to permit it to be presented to a machine such as a sewing machine for securing the upper permanently to the sole or insole without further lasting. Even in cases where it is found desirable to use the side 50 lasting machine on these or other kinds of shoes, any necessity for pulling the upper at the rear of the ball as a supplementary manual operation is entirely eliminated.

In the appended claims the term "sole" 55 is used generally for convenience to define that portion of the shoe to which the margin of the upper is fastened in lasting, irrespective of the type of shoe, and is thus inclusive of the insole of a welt or a McKay 60 shoe as well as of the sole of a turn shoe.

Having described the invention, what I claim as new and desire to secure by Letters Patent of the United States is:

1. In a machine of the class described, 65 the combination with last and upper posi-

tioning means, of upper pulling means comprising side gripper jaws having gripping faces arranged to extend rearwardly inward along the inward lateral curve of the edge of the shoe bottom at the rear end 70 of the ball of the shoe, and means controlled by engagement with that portion of the shoe along which said faces extend rearwardly inward for fastening the margin of the upper substantially at the rear end of 75 the ball of the shoe to hold it after it has been pulled.

2. In a machine of the class described, the combination with last and upper positioning means, of upper pulling means 80 comprising side gripper jaws having gripping faces arranged to extend rearwardly inward along the inward lateral curve of the edge of the shoe bottom at the rear end 85 of the ball of the shoe, said jaws also having their outer edges inclined similarly to the slope of the last bottom rearwardly of the ball line, and overlaying and fastening means arranged to be controlled by engagement with the portions of the side and 90 bottom faces of the shoe along which said inclined edges of the jaws extend for overlaying and for fastening the margin of the upper substantially at the rear end of the ball of the shoe to hold it after it has been 95 pulled.

3. In a machine of the class described, the combination with last and upper positioning means comprising side gripper jaws having continuous upper engaging faces the rear portions of which are inclined rearwardly inward relatively to the front portions for engagement with the margin of the upper 100 along the inward lateral curve of the edge 105 of the shoe bottom at the rear end of the ball of the shoe, means for effecting relative movement of said gripper jaws and the last to pull and to overdraw the upper, and means arranged to be positioned automatically by engagement with that portion 110 of the side of the shoe along which said faces are inwardly inclined for fastening the margin of the upper substantially at the rear end of the ball of the shoe to hold 115 it after it has been pulled.

4. In a machine of the class described, the combination with last and upper positioning means, of upper pulling means comprising side gripper jaws having gripping faces curved lengthwise of the shoe similarly to the lateral curve of the edge of the shoe bottom along the ball of the shoe and with the rear portions of said faces arranged to extend inwardly along the inward curve of 120 said edge at the rear end of the ball, said jaws also having their outer edges inclined similarly to the slope of the last bottom rearwardly of the ball line, means for effecting relative movement of said gripper 125 jaws 130

jaws and the last to pull and to overdraw the upper, and overlying and fastening means mounted for inward movement over the shoe substantially opposite to said rear portions of the gripper jaws and arranged to be controlled by engagement with that part of the shoe along which said rear portions of the jaws extend for overlaying and for fastening the margin of the upper substantially at the rear end of the ball of the shoe to hold it after it has been pulled.

5. In a machine of the class described, the combination with last and upper positioning means, of upper pulling means comprising side gripper jaws having gripping faces rearwardly curved in substantially parallel relation to the lateral inward curve of the edge of the shoe bottom at the rear end of the ball of the shoe, means for effecting relative movement of said gripper jaws and the last to pull and to overdraw the upper, and means mounted for inward movement over the shoe to a point determined by engagement with that part of the shoe 20 where said edge curves inwardly for driving a fastening near the rear ends of said jaws to hold the upper after it has been pulled.

6. In a machine of the class described, the combination with last and upper positioning means, of upper pulling means comprising front and rear pairs of side gripper jaws having the gripping faces of the rear pair arranged to extend rearwardly inward 35 along the inward lateral curve of the edge of the shoe bottom at the rear end of the ball of the shoe, power means automatically operative to position said jaws initially with the rear pair projecting transversely of the plane of the shoe bottom beyond the outer edges of the front pair and to impart to the rear pair of jaws a pulling movement longer than that of the front pair, and upper fastening means constructed and arranged to fasten the margin of the upper substantially 40 opposite to the rear ends of the rear pair of jaws to hold it after it has been pulled.

7. In a machine of the class described, the combination with last and upper positioning means, of upper pulling means comprising front and rear pairs of side gripper jaws having the gripping faces of the rear pair curved rearwardly in substantial conformity 50 to the inward lateral curve of the edge of the shoe bottom at the rear end of the ball of the shoe, means for positioning said jaws initially with the rear pair projecting transversely of the plane of the shoe bottom beyond the outer edges of the front pair and for imparting to the rear pair of jaws a pulling movement longer than that of the front pair, power means for causing said gripper jaws to overdraw the upper, and means automatically operative in time relation 55 to the overdrawing of the upper for

fastening the margin of the upper substantially at the rear end of the ball of the shoe.

8. In a machine of the class described, the combination with last and upper positioning means, of upper pulling means comprising front and rear pairs of side gripper jaws having the rear portions of the gripping faces of the rear pair of jaws inclined inward relatively to their front portions for engagement with the margin of the upper along the inward lateral curve of the edge of the shoe bottom at the rear end of the ball of the shoe, said rear pair of jaws also having their outer edges inclined similarly to the slope of the last bottom rearwardly of the ball line, power operated means for positioning said jaws initially with the rear pair projecting transversely of the plane of the shoe bottom beyond the outer edges of the front pair and for imparting to the rear pair a pulling movement longer than that of the front pair, and power means automatically operative subsequently to fasten the upper substantially at the rear end of the ball of the shoe to hold it after it has been pulled.

9. In a machine of the class described, the combination with last and upper positioning means, of upper pulling means comprising side gripper jaws having gripping faces arranged to extend rearwardly inward along the inward lateral curve of the edge of the shoe bottom at the rear end of the ball of the shoe, means mounted for movement into position to fasten the upper substantially at the rear end of the ball of the shoe, and overlaying means operatively movable laterally of the shoe and constructed and arranged to press the margin of the upper against the bottom face of the sole over the sloping surface of the last bottom at the rear of the ball line to hold it for the fastening operation.

10. In a machine of the class described, the combination with last and upper positioning means, of upper pulling means comprising side gripper jaws arranged to engage the upper along the ball of the last and rearwardly beyond the ball line, means for fastening the upper substantially at the rear end of the ball of the last, and overlaying means comprising a member confined substantially to engagement with a portion of the margin of the upper at the rear of said fastening point, and arranged to press said portion of the margin over the bottom of the last independently of control of other portions of the shoe.

11. In a machine of the class described, the combination with last and upper positioning means, of upper pulling means comprising side gripper jaws having gripping faces arranged to extend rearwardly inward along the inward lateral curve of the edge of the shoe bottom at the rear end of the ball

of the shoe, the outer edges of said jaws being inclined similarly to the slope of the bottom face of the last at the rear of the ball line, means for effecting relative movement of said gripper jaws and the last to pull and to overdraw the upper, and overlaying means comprising a plurality of overlaying members at each side of the shoe movable inwardly in engagement with the margin of the upper in locations substantially opposite to said gripper jaws, the different overlaying members at each side of the shoe being independently yieldable in accordance with variations in the contour of the bottom face of the last.

12. In a machine of the class described, the combination with last and upper positioning means, of upper pulling means comprising a pair of side gripper jaws arranged to engage the upper along the ball of the last and rearwardly beyond the ball line, the outer edges of said jaws being inclined similarly to the slope of the bottom face of the last at the rear of the ball line, and overlaying means comprising members movable inwardly in engagement with a portion of the upper pulled by said pair of jaws, said members being arranged to assume relative positions in accordance with the lengthwise slope of the bottom of the last.

13. In a machine of the class described, the combination with last and upper positioning means, of upper pulling means comprising side gripper jaws having gripping faces curved rearwardly in substantial conformity to the inward lateral curve of the edge of the shoe bottom at the rear end of the ball of the shoe, means for effecting relative movement of said jaws and the last to pull and to overdraw the upper, means for fastening the upper substantially at the rear end of the ball of the last, and overlaying means comprising members for engaging the margin of the upper respectively at opposite sides of said fastening point, said members being relatively yieldable in accordance with variations in the contour of the bottom face of the last.

14. In a machine of the class described, the combination with last and upper positioning means, of means for pulling the upper along the ball and beyond the rear end of the ball of the last including a gripper inclined inward laterally of the shoe along the inward curve of the edge of the last bottom beyond the rear end of the ball, and overlaying means comprising a member arranged to engage the margin of the upper over the rearwardly sloping surface of the last bottom at the rear of the ball and another member for engaging the margin of the upper on the ball of the last in front of said first member, said members being

relatively yieldable in accordance with variations in the contour of the bottom surface of the last.

15. In a machine of the class described, the combination with last and upper positioning means, of upper pulling means, overlaying means comprising members arranged respectively to engage portions of the upper at the ball of the last and beyond the rear end of the ball, said members being movable bodily inward along the surface of the upper, and controlling means constructed and arranged to permit said members to yield each independently of the other in accordance with the contour of the bottom surface of the last.

16. In a machine of the class described, the combination with last and upper positioning means, of upper pulling means, and overlaying means comprising members movable bodily inward along the surface of the upper and arranged respectively to engage portions of the upper at the ball of the last and beyond the rear end of the ball, said members being independently yieldable transversely of the plane of the shoe bottom in response to resistance of the shoe materials and also adjustable each independently of the other to determine their normal relation to the plane of the shoe bottom.

17. In a machine of the class described, the combination with last and upper positioning means, of pulling-over means, means for driving a fastening to hold the upper in its pulled-over position, and overlaying means comprising members constructed and arranged to engage the margin of the upper respectively at opposite sides of said fastening point to hold it for the fastening operation, said members being relatively yieldable in response to resistance of the materials on the shoe bottom.

18. In a machine of the class described, the combination with last and upper positioning means, of upper pulling means constructed and arranged to engage the upper at the ball of the last and also rearwardly beyond the ball, means for fastening the upper substantially at the rear of the ball of the last, and overlaying means comprising members arranged to engage the upper respectively at opposite sides of the fastening point, said members being independently yieldable in a direction transverse to the plane of the shoe bottom in response to resistance of the shoe materials.

19. In a machine of the class described, the combination with last and upper positioning means, of upper pulling means constructed and arranged to engage the upper at the side of the ball and also rearwardly beyond the ball of the last, upper fastening means comprising a tacker arranged to drive a tack at or near the rear end of the

ball of the last, and overlaying means comprising members arranged to engage the upper respectively at opposite sides of said tacker, said members being relatively yield-

tively to the other tackers in directions laterally of the shoe and having means for engaging the side of the shoe to determine its operative position. 65

5 able in a direction transverse to the plane of the shoe bottom and relatively adjustable to determine their normal relation to said plane.

23. In a machine of the class described,

20. In a machine of the class described, the combination with last and upper positioning means, of upper pulling means comprising a side gripper arranged to engage the upper along the ball of the last and beyond the rear end of the ball, said gripper having its rear portion inclined inward laterally of the shoe, upper fastening means comprising a tacker arranged to fasten the upper at or near the rear end of the ball of the last, operating means for moving said tacker inward laterally of the shoe, spring means tending to hold the tacker in an advanced position relatively to its operating means while permitting it to yield in response to resistance of the shoe materials, and overlaying means carried by said tacker for engaging the upper beyond the rear end of the ball of the last.

opposite sides of said tacker, said members being mounted to yield each independently of the other in a direction transverse to the plane of the shoe bottom in response to resistance of the shoe materials. 95

21. In a machine of the class described, the combination with last and upper positioning means, of upper pulling means comprising gripper jaws constructed and arranged to engage and pull the upper along the forepart of the last and extending inward laterally of the shoe for engagement with a section of the upper extending rearwardly beyond the ball of the last, and upper fastening means comprising a plurality of tackers movable laterally of the shoe to tack driving position, one of said tackers being arranged to drive a tack at or near the rear end of the ball of the last and mounted for yielding movement laterally of the shoe and relatively to the other tackers to permit relative conformation of the tackers to the lengthwise curvature of the lateral periphery of the shoe.

24. In a machine of the class described, the combination with shoe positioning means, of upper fastening means movable transversely of the edge of the shoe bottom 100 to operative position, overlaying members carried by said fastening means for engaging the margin of the upper respectively at opposite sides of the fastening point, and yielding means tending to move said overlaying members in a direction to depress their front ends relatively to the plane of the shoe bottom while permitting said members to yield each relatively to the other in response to the resistance of the shoe materials. 105 110

22. In a machine of the class described, the combination with last and upper positioning means, of upper pulling means comprising gripper jaws constructed and arranged to engage and pull the upper along the forepart of the last and extending inward laterally of the shoe for engagement with a section of the upper extending rearwardly beyond the ball of the last, and upper fastening means comprising a tacker arm movable laterally of the shoe, a plurality of tackers carried by said arm for driving tacks along the edge of the shoe bottom in front of the rear end of the ball of the last, and an additional tacker carried by said arm for driving a tack at or near the rear end of the ball, said last-named tacker being mounted to swing yieldingly and rela-

25. In a machine of the class described, the combination with shoe positioning means, of upper fastening means movable transversely of the edge of the shoe bottom 115 to operative position, and overlaying members carried by said fastening means for engaging the margin of the upper respectively at opposite sides of the fastening point, yielding means tending to move said overlaying members in a direction to depress their front ends relatively to the plane 120 of the shoe bottom while permitting them to yield in response to resistance of the shoe materials, and means for effecting a relative 125 adjustment of said members to determine their normal relation to the plane of the shoe bottom.

26. In a machine of the class described, the combination with shoe positioning means and pulling-over means, of means for fastening the upper in pulled-over position, and overlaying means comprising members arranged to engage the upper respectively at opposite sides of the fastening point, said members being pivoted to swing yieldingly and relatively to each other in a direction transverse to the plane of the shoe bottom in response to resistance of the shoe materials.

27. In a machine of the class described, the combination with shoe positioning means, of a tacker movable transversely of the edge of the shoe bottom to tack driving position, overlaying means carried by said tacker and comprising members pivoted to swing relatively to each other in directions transverse to the plane of the shoe bottom, and yielding means tending to swing said members in a direction for applying pressure to the upper materials on the shoe bottom while permitting them to yield in response to resistance of the shoe materials.

28. In a machine of the class described, the combination with shoe positioning means, of overlaying and fastening mechanism comprising a tacker arm movable transversely of the edge of the shoe bottom to tack driving position, a tacker pivotally mounted on said arm to swing yieldingly in directions transverse to the lateral periphery of the shoe and having means for engaging the shoe to determine its operative position, and an overlaying member carried by said tacker for engaging the margin of the upper adjacent to the tacking point, said member being mounted for yielding movement relatively to the tacker in response to resistance of the shoe materials.

29. A machine of the class described having, in combination, means for gripping and pulling over a last the sides of an upper including a portion of the upper extending along that portion of the edge of the shoe bottom which curves inwardly toward the shank of the shoe, and means for overlaying and fastening the margin of the upper comprising a fastening device arranged to be positioned laterally of the shoe by engagement with that portion of the side face of the shoe where said edge curves inwardly.

30. A machine of the class described having, in combination, means for gripping and pulling over a last the sides of an upper including a portion of the upper extending along that portion of the edge of the shoe bottom which curves inwardly toward the shank of the shoe, and means for inserting a plurality of upper securing fastenings along the side of the shoe including a rear fastening device arranged to

position itself laterally of the shoe independently of the remainder of said fastening means by engagement with that portion of the side face of the shoe where said edge curves inwardly.

31. A machine of the class described having, in combination, means for gripping and pulling over a last the sides of an upper including a portion of the upper extending along that portion of the edge of the shoe bottom which curves inwardly toward the shank of the shoe, and means for overlaying and fastening the margin of the upper comprising an overlaying device movable over that portion of the shoe bottom where said edge curves inwardly and automatically conformable to the lengthwise contour of the bottom face of the shoe rearwardly of the ball line.

32. A machine of the class described having, in combination, means for gripping and pulling over a last the sides of an upper including a portion of the upper extending along that portion of the edge of the shoe bottom which curves inwardly toward the shank of the shoe, and overlaying and fastening means comprising an overlaying device initially adjustable in approximate conformity to the lengthwise contour of the bottom face of the shoe rearwardly of the ball line and further conformable automatically to said contour in the operative movement of the device over the shoe.

33. A machine of the class described having, in combination, means for gripping and pulling over a last the sides of an upper including a portion of the upper extending along that portion of the edge of the shoe bottom which curves inwardly toward the shank of the shoe, means for inserting a fastening to secure the margin of the upper at that portion of the shoe where said edge curves inwardly, and overlaying means arranged to engage the margin of the upper at the front and at the rear of said fastening point with the rear portion of said means positioned to extend farther inward laterally of the shoe than the front portion.

34. In a machine of the class described, the combination with means for pulling an upper over a last, of fastener inserting means mounted for inward movement over the bottom of the shoe, and a pair of overlaying rolls mounted for inward movement with said fastener inserting means and arranged to engage the margin of the upper respectively a opposite sides of the fastening point.

In testimony whereof I have signed my name to this specification.

BERNHARDT JORGENSEN.
